UNITED STATES PATENT OFFICE.

CHARLS KOEGEL, OF HOLYOKE, MASSACHUSETTS.

WINDING AND SLITTING MACHINE.

SPECIFICATION forming part of Letters Patent No. 577,865, dated March 2, 1897.

Application filed October 29, 1895. Serial No. 567,311. (No model.)

To all whom it may concern:

Be it known that I, CHARLS KOEGEL, a citizen of the United States of America, residing in Holyoke, in the county of Hampden and State of Massachusetts, have invented new and useful Improvements in Winding and Slitting Machines, of which the following is a specification, reference being had to the accompanying drawings and letters and figures of reference marked thereon.

The object of my invention is to provide a machine by which paper or other material may be closely wound and formed into a thoroughly-compact mass and with which the material may be cut during the process of rolling and compacting, producing a series of rolls the sides of which will be uniform.

My object is, further, to provide a device wherein the cutting operation will be performed after the material is wound in part upon the spool, thus avoiding all inaccuracies resulting from cutting before the material reaches the spool, thus avoiding the formation of a completed roll having uneven sides and avoiding defects resulting from the unequal stretching of the strips after separation.

My object is, further, to provide a device in which the cutters will at all times be automatically maintained in the same relative position to the material.

My object is, further, to provide a device for rolling and cutting wherein the position of the cutters with reference to the material is regulated and controlled by the roll of material itself.

My object is, further, to provide a machine wherein disks of closely-wound paper or other material may be formed which will be uniform and accurate, and also to produce an improved machine wherein a better result is attained than has been heretofore reached.

I accomplish the objects of my invention by the construction herein shown.

In the accompanying drawings, in which like letters and numerals of reference indicate like parts, Figure 1 is a perspective view of my improved machine. Fig. 2 is a front elevation, on an enlarged scale, showing a part of the vertical side portions of the frame, showing also the boxes and shafts mounted in place. Fig. 3 is a plan view of one of the upper sliding boxes. Fig. 4 is a like view of one

of the fixed boxes and gear-supports. Fig. 5 is a plan view of a portion of the rear part of the machine. Fig. 6 is a view, on an enlarged scale, of the operative mechanism mounted in the frame at one side, as seen from the back of the machine, the portion of the frame at the right of Fig. 2 being selected for this illustration and the frame being shown only in dotted lines; and Fig. 7 is a view, on an enlarged scale, of the mechanism mounted upon the upper end of the frame at the right of Fig. 1, but looking from the rear.

In detail, A indicates the vertical side parts of the machine-frame. B indicates boxes secured in fixed position to said uprights. C indicates sliding boxes arranged in suitable ways in said uprights above the fixed boxes. D indicates like boxes mounted in suitable ways in said vertical parts below the fixed boxes. E indicates a spool-shaft; F, a presser and regulating roll; G, a cutter-shaft; H, disk cutting-blades; I, a spool mounted on the spool-shaft; J, a guide-roll. K indicates the material being wound or rolled and pressed; L, a shaft upon which the material is mounted before being operated upon; M, N, and O, gears; P, sprocket-wheels; Q, sprocket-chain; R, bevel-gear; S, threaded rods; T, bevel-gear; U, tie-rods or frame-braces; V, a pulley mounted on the cutter-shaft; W, a belt conveying motion to said pulley; X, a pulley mounted on the main driving-shaft; Y, an idler, and Z a brake-pulley.

a indicates spur-gears mounted on the back of the fixed boxes.

c indicates racks secured at one end to the upper sliding boxes.

d indicates racks adjustably fixed at one end to the lower sliding boxes; e, latches pivotally mounted on the ends of the fixed boxes; f, latches mounted on said boxes to engage the first-mentioned latches; g, handles on the ends of the spool-shaft; i, a hand-wheel; k, hangers for the bearings of guide-roll J; o, main driving-shaft; p, clutch; y, idler-arm, and y' weight on idler-arm; 2, offsets or lugs on the back of the upper sliding boxes; 3, adjusting-screws engaging the lower sliding boxes; 4, lugs on the back of the lower sliding boxes; 5, arms extending from the lower end of racks d to and engaging the adjusting-screws 3.

The construction and operation of my device may be briefly described as follows.

- 5 Mounted in a suitable frame is a spool-shaft carrying a spool upon which the material is compressed or tightly rolled and wound and at the same time cut in any desired width or widths, the cutting operation being performed after the material is in contact with and in part wound upon the completed roll.
- 10 Before being operated upon the material is supported upon a shaft and may be located at any convenient point, preference of course being given to mounting said shaft in the machine-frame. The material is conducted from
- 15 the supply-roll over a guide roll or rolls and thence to the presser-roll. The presser-roll is mounted in boxes having sliding movement in the frame, so that as the size of the roll in process of formation increases in diameter the
- 20 presser-roll will be lifted thereby.

The cutters consist of rotary disks mounted upon a revolving cutter-shaft, which shaft is mounted in sliding boxes, which also move away from the roll in process of formation as its diameter is increased, this movement being controlled by the roll in process of formation operating upon a roll in contact therewith.

I prefer that the presser-roll act as a regulating or controller roll for the cutter-shaft, but it will readily be seen that an independent controller-roll may be employed, it being operatively connected with the sliding boxes in which the cutter-shaft is mounted in the

25 same manner as illustrated by me with reference to the presser-roll.

Referring now to the detail of construction, a suitable frame is provided, having vertical side posts A, which posts are provided with

30 suitable ways in the front portion thereof, in which ways are mounted the upper sliding boxes C and the lower sliding boxes D. The boxes B, in which the spool-shaft E has bearings, are fixed in position upon said posts.

35 A main driving-shaft o is suitably mounted in the portion of the frame at the rear of the posts, which shaft is provided with fast and loose pulleys in the common well-known manner. A clutch p of any convenient form of

40 construction is arranged upon said shaft to engage and drive a spur-gear O, also mounted upon said shaft. The main driving-shaft is provided at its opposite end portion with a pulley X, carrying a belt which passes over

45 a pulley V, mounted upon the cutter-shaft G, and thereby causes the cutter-shaft to revolve; and to keep this belt taut at all times I prefer to employ the common form of idler shown in the drawings in Fig. 5 and an arm

50 y, pivotally mounted and provided at one end with an idler-pulley Y and at its opposite end with a weight y', thus avoiding danger of the stopping of this belt and insuring the rotation of the cutters and the consequent

55 perfect cutting operation.

The spool-shaft E is provided with a spur-gear M and receives motion from the spur-

gear O, mounted upon the main driving-shaft, through the operation of an intermediate spur-gear N, mounted upon a suitable 70 stud upon the frame, so that the cutters may be put in motion first and then through the operation of the clutch the spool-shaft may be caused to revolve, this being desirable to prevent danger of tearing the material, which 75 might result if both the roll of material and cutters started at the same time, and as the cutters might be slightly irregular a nicer adjustment of them to the material can be made when they are controlled independently of 80 the material.

The rear portion of the machine is provided with suitable bearings, in which is mounted a shaft L, carrying the supply of material to be operated upon. The upper portion of the posts at the rear are provided with suitable hangers k, supporting boxes in which a shaft carrying a guide-roll J has bearings.

The cutters consist of independent disk blades, mounted upon the cutter-supporting 90 shaft G, and collars, rings, or other separating devices are arranged between their faces to give the requisite separation.

The spool-shaft E is provided with a spool I, mounted thereon, upon which spool the material is wound.

Z is a pulley mounted on the supply-roll shaft L, upon the periphery of which pulley a shoe bears, the tension on the pulley being produced by a weighted lever or a spring 100 bearing the shoe toward the pulley.

U are stay-rods or braces extending from side to side of the frame.

At each side of the frame and mounted at the top thereof are sprocket-wheels P, having 105 their central openings threaded or by preference being mounted upon threaded nuts and connected by a sprocket-chain Q, and secured to one of these sprocket-wheels is a spur-gear R. A like spur-gear is mounted 110 at one side on a suitable support, the teeth of which gear mesh with the teeth on the bevel-gear R. The hand-wheel i is mounted upon the shaft carrying the bevel-gear T, so that a revolution of the hand-wheel will operate through the medium of the bevel-gears to cause one sprocket-wheel to be revolved and through the operation of the sprocket-chain cause the other sprocket-wheel to be revolved to the same extent.

The rods S and S' are exteriorly threaded to engage the threads in the nuts or interior threaded portion of the sprocket-wheels. It will now be seen that if these rods be restrained from turning the revolution of the 125 sprocket-wheels will cause them to be moved up or down, dependent upon the direction of revolution of the sprocket-wheels. These rods are each provided with a longitudinal slot or groove, and their lower ends pass 130 through an offset or shoulder 2 on the back side of the boxes C and are prevented from revolving therein by a set-screw or key entering the slot, so that if the movable boxes

C be fixed in position the rods S would be free to move vertically in either direction through the opening in the offset 2 and would be prevented from rotating therein. The upward movement, however, in this offset is limited by a nut on the end of each rod, and the downward movement is limited only by the length of the threaded rods. The sliding boxes C, however, are free, as before stated, to move up and down in suitable ways in their supporting-frame, carrying with them, of course, the presser and regulating roll F.

Racks c, having teeth upon their inner edges, are secured at their upper ends to the boxes C, the frame being provided with suitable ways for the racks. The fixed boxes B have mounted upon their inner faces spur-gears a, the teeth of which mesh with the teeth on the racks c, so that the moving of the sliding boxes C either up or down will cause the spur-gears a to revolve in a direction dependent upon the direction of the movement of the sliding boxes C.

The sliding boxes D, which carry the cutter-shaft G, have secured to them and projecting upwardly therefrom racks d of like construction as the racks secured to the boxes C, as before described, so that the revolution of the spur-gear a, caused by the upward or downward movement of the sliding boxes C, will give a like extent of movement, but in reverse direction, to the boxes D.

To provide for the proper adjustment of the cutter-blades with reference to the material being operated upon, the racks d, mounted upon the sliding boxes D, instead of being immovably fixed thereto are adjustably mounted thereon by the employment of adjusting-screws 3, which have threaded connection with the offsets or lugs 4 on the back side of the sliding boxes D. The racks d have secured to them and projecting toward the center of the frame-posts arms or offsets 5, having forked openings in their ends to receive the head of the adjusting-screw 3, which is provided with an annular recess, so that a part of the head is above and a part below the arms 5, and by turning the set-screws 3 in the desired direction the relative position of the knives with reference to the spool may be varied.

The roll J is a guide-roll in the sense that it serves to guide the paper or other material in its passage from the supply-roll to a position where it may be led conveniently to the location where it is to be operated upon.

The roll F is a regulator or controller roll in the sense that it by contact with the material as it is wound upon the receiving-spool determines the position of the cutters with reference to the material, for it will readily be seen that as the material is wound upon the spool the diameter of the spool is increased, the roll F thereby raised or moved outwardly, and through the mechanism before described the cutters are carried away from the spool,

so that the roll F serves as a guide or controller to determine the position of the cutters with reference to the material.

The material to be operated upon is carried from the supply at the back of the machine upwardly over an idler or guide-roll J and downwardly in front of the roll F and wound upon the spool sufficiently to cause it to bight. The hand-wheel i is then turned in a direction to lower the sliding boxes C, carrying the roll F, until the roll F rests upon the material and is sustained thereby, so that at that time the nuts upon the ends of the threaded rods S will not bear against the offsets 2 on the sliding boxes C. The lowering of the boxes C will, through the operation of the racks c and d and the intermediate spur-gear a, operate to carry the sliding boxes D upwardly, thereby bringing the cutter-shaft G to a position where the edges of the cutters will be in contact with the material upon the spool, at which time, if the cutter-blades do not occupy the desired accurate position, they may be adjusted upwardly or downwardly by the adjusting device operatively arranged between the sliding boxes D and the racks d. The machine being now started, the roll will increase in diameter. The roll F will thereby be moved away from the spool-shaft, causing the sliding boxes C to move upwardly, carrying their racks with them, the spur-gear a being thus caused to revolve in a direction to carry the racks d and the sliding boxes D with them downwardly, thus carrying the cutter-shaft G and cutters away from the spool-shaft, the threaded rods remaining at rest and projecting through the offsets a to an extent dependent upon the upward movement of the sliding boxes C, caused by the upward movement of the roll F, caused by the increasing size or diameter of the roll being formed.

When it is desired to remove the finished roll or rolls from the spool-shaft or for any purpose to maintain the roll F and the cutter-shaft separated from the spool-shaft or material, it simply becomes necessary to turn the hand-wheel i in a direction to cause the threaded rods S to move upwardly until the nuts upon their ends engage the offsets on the boxes C, and a continued turning of the hand-wheel will result in moving these boxes upwardly and with them the roll F away from the material, where they will remain until the hand-wheel be again turned to place the parts in the desired operative position, the cutter-shaft being moved in each instance a like distance, but in reverse direction.

When the parts are in position and so adjusted that the cutters will cut through one thickness of material, the machine may be started, and as the material is wound upon the spool it is cut into strips dependent upon the distance of separation of the cutting-blades, and at the same time it is wound with a degree of firmness, closeness, and solidity

dependent upon the pressure of the roll F upon the material. The weight or pressure upon the material may be varied as required by substituting other rolls of different weight.

5 It will of course be readily seen that the pressure and guide roll might be made separate, *i. e.*, two rolls be employed, one for the purpose of giving the requisite tension or pressure and one as a guide and operatively connected 10 with the intermediate adjusting or guiding mechanism, without departing from my invention. I prefer, however, that one roll be used both for pressure and regulator.

The winding or rolling of the material before it is cut insures perfect accuracy in the completed roll, while if the cutting operation be performed before the material is wound perfect registry at the edges will not result. At least inaccuracies are liable to occur, which 20 will leave the sides of the finished roll uneven.

Having, therefore, described my invention, what I claim, and desire to secure by Letters Patent, is—

1. In a winding and slitting machine, the 25 combination, with a suitable frame, of a winding-spool, a regulator arranged to be moved outwardly from the axis of the spool by the increasing thickness of the material wound thereon, and cutters mounted on a cutter-shaft (other than the regulator) and arranged to cut the material after it reaches the roll being formed, the cutter-shaft being arranged to be moved away from the spool-axis by the outward movement of said regulator, substantially as described.

2. In a winding and slitting machine, the 30 combination, with a suitable frame, of a winding-spool, a regulator-roll arranged to be moved by the change in diameter of the roll 40 of material upon the spool and a cutting-shaft having cutting-blades mounted thereon, and intermediate operative mechanism whereby the relative position of the material upon the spool and the blades is varied by the regulator, the cutter-shaft being supported independently of the material and independently of the body of the regulator-roll substantially as shown.

3. In a winding and slitting machine, the 45 combination, with a suitable frame, of a winding-spool, a regulator-roll arranged to be moved outwardly from the axis of the spool by the increase in diameter of the roll being formed and a cutting-shaft having cutting-blades mounted thereon and mounted in sliding boxes, whose position is controlled by operative mechanism interposed between them and the regulator, substantially as shown.

4. In a winding and slitting machine, a suitable frame, a winding-spool, a controller bearing against the material being wound, means for cutting the material as it is being wound, said cutting means being supported and operated by mechanism independent of the material being operated upon, and operative mechanism between the controller and cutting mechanism, whereby the position of the

cutters with reference to the material is controlled by the controller, substantially as shown.

5. The combination of a suitable frame, a controller movably mounted therein, a spool and cutters one being movable with reference to the other, intermediate mechanism whereby the controller determines the relative position between the spool and cutters and means other than the material being operated upon to drive the cutter-shaft, substantially as shown.

6. In a winding and slitting machine, the 80 combination, with a suitable frame, of a winding-spool, a presser regulator-roll to press the material as it is wound upon the spool, cutters arranged to cut the material on the roll at a point removed from the presser-roll, means 85 to support and communicate motion to the cutters other than through the medium of the presser-roll, and an operative connection between said presser-roll and cutters whereby the outward movement of the presser-roll 90 from the spool will also move the cutters outwardly, substantially as described.

7. In a winding and slitting machine, the combination, with a suitable frame, of a winding-spool, mechanism for driving the same, a 95 cutter-shaft having cutters thereon arranged to cut the material as it is partly wound, mechanism for driving the same, a regulator arranged to be moved outwardly from the axis of the spool by the increase of the diameter 100 of the roll being formed and an operative connection between said regulator and said cutter-shaft whereby the latter is moved away from the winding-spool in unison with the former, substantially as described.

8. In a winding and slitting machine, the combination, with a suitable frame, of a winding-spool, a regulator resting upon and supported by the material being wound and arranged to be moved outwardly from the axis 110 of the spool by the increase in the diameter of the roll being formed, and cutters for slitting said material, the cutters being mounted in supports and operative independently of the regulator-roll and arranged to be moved 115 away from the spool and in opposite direction by the outward movement of said regulator, substantially as described.

9. In a winding and slitting machine, the combination, with the vertical side posts, the 120 fixed bearings B therein, the winding-spool shaft in said bearings, the vertically-sliding bearings C, D, in said posts, the roll F and shaft G having cutters H, mounted in said bearings, respectively and an operative connection between the bearings C and D whereby they move oppositely from each other in unison, substantially as described.

10. In a winding and slitting machine, the combination with the sides of the machine, 130 of three pairs of bearings each pair carrying a roller or shaft, whereof one is a presser-roller, another a spool-shaft, and a third is provided with cutting-blades, said bearings

on each side being movable relatively to each other but operatively connected so that the presser-roller bearings and the cutter-shaft bearings are always moved equidistant from the spool-shaft bearing, substantially as described.

11. In a winding and slitting machine, the combination, with the lateral supports of the machine, of the stationary bearings thereon, the stationary spur-gears, the movable bearings on said supports, each pair thereof provided with racks meshing with said spur-gears on opposite sides, and the rollers carried by said bearings, substantially as described.

12. In a winding and slitting machine, the combination, with the vertical side posts, of the fixed bearings and winding-shaft therein, a fixed spur-gear, the upper sliding bearings having a presser-roll therein and provided with a rack, the lower sliding bearings having a slitting-shaft therein and provided with a rack, said racks engaging said spur-gear so as to effect a reciprocal motion, one from the other, substantially as described.

13. In a winding and slitting machine, the combination, with vertical side posts, of fixed bearings therein, a winding-spool shaft in said bearings, a presser-roll above said winding-shaft, a cutter-roll below the same, bearings for said presser-roll and cutter-roll, moving oppositely in unison and means, for moving both presser-roll bearings simultaneously, substantially as described.

14. In a winding and slitting machine, the combination, with suitable slideways, of the bearing C, having the racks c, the bearings D having the racks d, the spur-gear a, meshing with said racks whereby they move oppositely in unison, the threaded stems S, S' arranged to engage said bearings C, and the threaded sprocket-wheels through which said stems pass and the sprocket-chain, whereby simultaneous reciprocation is imparted to said stems, substantially as described.
